UNITED STATES PATENT OFFICE

HALFDAN J. NORDSETH, OF SAN FRANCISCO, CALIFORNIA, ASSIGNOR TO THE SIDLEY CO., OF SAN FRANCISCO, CALIFORNIA, A CORPORATION OF CALIFORNIA

SEPARABLE FASTENER

Application filed October 23, 1929. Serial No. 401,891.

The present invention relates to improvements in separable fasteners, and an object is to provide a fastener in which a double hook is employed for fastening the loose end of a 5 garter band to the conventional pad employed as a joining means for the two ends of the garter band.

It is further proposed in the present invention to arrange the two hooks in such a manner that both of them will lie in the normal 10 line of pull exerted by the tension of the garter band. It is further proposed to provide a special means for fastening a stud plate to the garter pad in such a manner that 15 pull exerted on the studs will not tend to tilt the stud plate so as to drive the front edge thereof into the flesh of the wearer and create a certain amount of discomfort. It is further proposed in the present invention to 20 provide a garter in which symmetry is substantially preserved on opposite sides of the vertical center line of the garter pad so that the pull exerted by the elastic band at opposite sides affects the same substantially in the 25 same way whereby a well balanced garter is produced.

Further objects and advantages of my invention will appear as the specification proceeds.

30 The preferred form of my invention is illustrated in the accompanying drawing, in which

Figure 1 shows a front view of my garter, 35 Figure 2 a sectional view as seen on line 2-2 of Figure 1;

Figure 3 a detail view of an eye-piece forming a part of my garter fastening means; and

Figure 4 a detail view of a stud plate adapted for cooperation with the eye-piece.

40 While I have shown only the preferred form of my invention, I wish to have it understood that various changes or modifications may be made within the scope of the claims hereto attached without departing from the spirit of 45 the invention.

In its preferred form my garter comprises a garter band 1, a garter pad 2, the fastening means indicated at 3 which forms the principal part of the present invention, and a second conventional fastening means 4 adapted for fastening the garter to the top of a 50 man's sock or the like.

It will be noted that my garter band is very wide which as a rule is considered a superior 55 feature, but which offers certain difficulties in the means for suitably fastening the band so as to prevent slipping and side-sway. In the present invention the construction of the fastening means is such that the entire garter band is always firmly held in place and is 60 made to lie closely against the leg of the person wearing the same.

The pad 2 which may be of any suitable 65 form is preferably made in the shape indicated in the drawing so as to be practically symmetrical on opposite sides of a vertical center line, and to present two edges 5 and 6 corresponding in length to the width of the band, and arranged at an angularity which allows the band to naturally assume the 70 slightly inclined position it normally occupies when in use.

75 My fastening means consist of an eye-piece 7 shown in detail in Figure 3, and a stud plate 8 shown in detail in Figure 4. The latter includes a bar 9 which is rather thin and narrow, and which terminates at each end in an enlargement 10, preferably circular in form and slightly offset from the bar 9 in such a manner that the two studs 11 rising 80 from the centers of the two enlargements lie in a line slightly forward of the front edge of the bar 9. The latter bar is intended to be stitched on the pad as shown at 12, and its front edge 13 is serrated as shown in Figure 4 to prevent the thread from sliding sideways. Shoulders 14 are formed at the ends of the rear edge of the bar 9 to prevent the thread from slipping. The studs are preferably made to include a comparatively short 85

shank 15 and a head 16, the idea of the shank being to allow the eye-piece to engage with the stud in close confinement between the head and the stud plate so as to eliminate a tendency to tilt. It should be noted that when the bar 9 is stitched to the pad it lies parallel to the edge 6 of the pad so that the pull exerted on the pad operates in the same direction as it would if the garter band were fastened directly to the edge 6.

The eye-piece 7 consists of a thin plate of metal or other suitable material formed as shown in Figure 3 and provided with a slot 17 corresponding in length to the width of the band so that the latter may be passed through the slot and fastened upon itself in the conventional manner by a buckle 18. From the body portion containing the slot extend two eyelets 19, each eyelet presenting a large entrance opening 20 for the head of the stud, and a narrowed opening 21 adapted to engage with the shank of the stud, and to be locked against the head. It will be noted particularly that in this form the eyelets do not communicate with the slot 17 and that it is impossible for instance for one edge of the garter band passing through the slot 17 to work itself into one of the eyelets and to thereby throw the garter off its balance. It should also be noted that the enlargements 10 of the stud plate are of somewhat larger diameter than the entrance openings of the eyelets so that accidental engagement of the eyelets with the stud plate itself is prevented.

The advantages of the double fastening means will be readily understood particularly where a wide band is employed. The garter when fastened in the manner proposed in this invention will be held firmly in place, and will neither slip nor swing. The fact that the two studs are fastened to the stud plate slightly in advance of the bar 9 is of importance, particularly in conjunction with the short shanks employed, since tilting of the stud plate is entirely eliminated and the pull of the garter band is transmitted to the pad practically in a straight line without any intervening lever action of the stud plate. The stitching of the stud plate to the garter is superior to other fastening means in so far as the spring is longer and consequently stitched more securely. The thread is firmly held in place by the shoulders 14 and each individual turn of the thread is held against movement in one of the serrations 13.

I claim:

1. A separable fastener comprising a stud plate shaped like a bar and having a substantially circular enlargement at each end, a headed stud rising from each enlargement, and an eye piece having a slot and two eyelets in non-communicating relation to the slot, said eyelets being large enough to receive the stud heads, but smaller than the circular

enlargements for preventing accidental engagement of the eyelets therewith.

2. A stud plate for a garter comprising a bar having a stud at each end, the bar being serrated between the studs so as to hold thread used for stitching the bar to a garter pad against slipping.

3. A stud plate for a garter comprising a bar having a stud at each end, the bar being serrated at one edge and having stops associated with the other edge to confine thread used for stitching the bar to a garter pad.
